INVENTOR:

Hans Sturm

BY: Francis E. Boyce

ATTORNEY

UNITED STATES PATENT OFFICE.

HANS STURM, OF REICHENBERG, CZECHOSLOVAKIA.

ARTIFICIAL TOOTH.

Application filed February 11, 1925. Serial No. 8,319.

To all whom it may concern:

Be it known that I, HANS STURM, citizen of Czechoslovakia, residing at 6 Altstädter Platz, Reichenberg, Czechoslovakia, have invented Improvements in an Artificial Tooth, of which the following is a specification.

This invention relates to an improvement in an artificial tooth having a metallic back-plate, as described in the German Patent 10 216,271. The improvement according to this invention consists essentially in the fact that the anchor for the tooth is made as a resilient loop, for instance of oval or polygonal shape, by means of which it may be resiliently introduced into a similarly formed recess in the tooth.

In order to avoid breaking the porcelain tooth while introducing the resilient anchor, according to this invention a certain reduction in the spring power of the loop may be brought about. This, for instance, may be attained by making the loop as a separate part from a very thin metal strip and soldering the same to the metallic back-plate. 25 A further reduction in spring power may be obtained by having the loop weakened or cut open longitudinally at certain places.

According to the form of the loop as mentioned, in the tooth itself there is provided a 30 recess, the walls of which will be in contact with the anchor after being introduced. In order to prevent recoil of the loop due to its resiliency and in order to completely hold the anchor in position, the hollow space surrounded by the loop before being introduced 35 into the tooth, according to this invention may be filled up with cement.

The loop, in case of a so-called pivot-tooth, may also be fixed relatively to the 40 base of the tooth and the interior walls of the recess by introducing a pin of proper cross-section through said base against the interior walls of the loop after being inserted into said recess. A cement filling for 45 the hollow space of the loop may be used in addition to this.

The resilient anchor according to this invention is made in an especially simple and expeditious manner by forming a V-shaped 50 metal plate which may be integral with the metallic back-plate of the tooth or united therewith after being formed, placing said plate between a supporting mandrel or core of the desired form and a pair of tongs of like form, and giving the final shape to said

plate by compressing the opening of the tongs.

In the drawing a tooth according to this invention is shown, as well as the new process of making the anchor for said tooth. 60 Fig. 1 is a cross-section of a tooth constructed in accordance with this invention showing the same before attachment of the back plate, Fig. 2 a longitudinal section taken centrally through Fig. 1, Figs. 3, 4 and 5 illustrate the loop in different stages of its development, Fig. 6 is a cross-section of a tooth in completed condition, Figs. 7 and 8 illustrate modified forms of the loop, Fig. 9 is a longitudinal section through a completed pivot-tooth, Figs. 10 and 11 show a further modification of the mode of fixing the looped anchor upon the back-plate, and Fig. 12 is a fragmentary side view of a pair of tongs suitable for the formation of the 70 loop.

In Figs. 1 and 2 an artificial tooth *a* is shown which is provided with a polygonal recess *b* for the reception of an anchor. In order to form the anchor itself, a metal 80 sheet *c* made for instance from gold, is bent into the cross-sectional form shown in Fig. 3. This plate is then fastened separately upon a supporting sheet of metal by means of soldering the same thereto. Fig. 4 shows 85 the rear-view of a metal plate *d* together with the loop *c*, which is cut out and bent as shown in Fig. 3. In order to give to the anchor the polygonal loop shape shown in Fig. 1 a core of proper form is introduced 90 into the space formed between the legs of the V-shaped portion of the loop and the latter is pressed upon this core by means of a pair of tongs having a properly formed opening, so that the loop will finally have 95 the shape of the anchor *e* shown in Fig. 5. This anchor is resilient in lateral direction and may therefore be readily introduced into the opening of recess *b* of the tooth *a*. Fig. 6 shows the anchor after being united 100 with the tooth. The hollow space surrounded by the anchor before being introduced into the tooth is provided with a cement filling and in this manner a wedge will be formed, which will nullify the resiliency of 105 the anchor and prevent the same from coming out of the recess of the tooth.

In Figs. 7 and 8 two ways are shown for purposes of reducing the spring power of the anchor, in order to avoid destruction of the 110

tooth, when introducing the anchor. For this purpose in Fig. 7 the wall of the loop is weakened as shown at *h* and in Fig. 8 said wall is slit as shown at *i*.

- 5 Fig. 9 shows an example of a pivot-tooth in longitudinal cross-section, which tooth is provided with an anchor in the form of a loop in the manner above indicated. In this case the loop, in addition to this, is fastened by means of a pin *k* to the metallic back-plate *d* which is integral with the pin *j*, said pin *k* being inserted from below through the under part of the plate *d* against the wall of the loop.
- 10 15 According to Figs. 10 and 11 a rectangular opening 1 is cut out in the back-plate *d*, said opening serving for the introduction of a loop such as that shown in Fig. 3 in the

manner shown in Fig. 11, the flaps *m* of the loop being soldered to the rear of plate *d*.
20 The loop, moreover, is formed and united with the tooth in the manner above described.

Having thus described my said invention, I declare that what I claim is:—

25 The combination with an artificial tooth having a recess, of a back plate, a polygonal loop adapted to receive cement and connected to the back plate, said loop fitting within the recess and interlocked with the tooth, and a vertical pin extending through the back plate and fitting within the loop at the front thereof and additionally fastening the loop to the back plate.

30 In testimony whereof I affix my signature.
DR. HANS STURM.
